[57] CLAIM

The ornamental design for a shoe covering, as shown and described.

DESCRIPTION

FIG. 1 is a perspective view of a shoe covering showing my new design in a position of use;

FIG. 2 is a top plan view thereof;

FIG. 3 is a side elevational view thereof, it being noted that the side opposite is identical; and,

FIG. 4 is a rear end elevational view thereof.

The broken line showing of a shoe in FIGS. 1, 3 and 4 is for illustrative purposes only and forms no part of the claimed design.
